UNITED STATES PATENT OFFICE

DON V. TANTLINGER, OF SHERMAN, CALIFORNIA

BOOMERANG

Application filed April 3, 1928. Serial No. 266,953.

This invention relates to an improvement in the construction of boomerangs for use either as weapons or for the purpose of amusement.

5 An object of the invention is to lessen the cost of manufacture of the article, and at the same time to increase its efficiency.

The invention relates to a boomerang of a composite character, one advantage gained 10 by thus constructing the article being that the two arms of the boomerang may be more conveniently secured together at a right angle to each other.

15 A further object of the invention is to produce a boomerang especially well adapted for being thrown by a manually operable appliance.

Other objects and advantages may herein-after appear.

20 Referring to the accompanying drawings which illustrate a preferred embodiment of the invention,

Figure 1 is a side elevation of a boomerang designed, when thrown, to be spun in the direction indicated by the arrow on said view.

25 Figure 2 is an edge view of Figure 1 looking from the top.

Figure 3 is an edge view thereof looking from left to right of Figure 1.

30 Figure 4 is a section of one of the arms on line 4—4 of Figure 1.

Figure 5 is a section of the other arm on line 5—5 of Figure 1.

35 Figure 6 is a side elevation of a boomerang designed, when thrown in the same direction as the boomerang of Figure 1, to be spun in the direction indicated by the arrow in said view.

Figure 7 is a section on line 7—7 of Figure 6.

40 Figure 8 is a section of the other arm on line 8—8 of Figure 6.

Referring in detail to the drawings, as 45 shown in Figure 1 the boomerang consists of a relatively long pointed arm 7 to which is attached a somewhat shorter blunt arm 8.

As shown in Figure 2, the arm 7 is curved to one side at 9 throughout about the outer third of its length. The base portion 11 of 50 said arm is considerably thickened and is

joined, in the illustrated embodiment of the invention, at a right angle to the thickened base portion 12 of the outer arm 8. Said arm 8 has a curved, deflected portion 13 which occupies about the outer half of its length. 55

The bow in each of the arms of the boomerang shown in Figures 1 to 5 is away from the flat side of the arm and toward the side thereof which has the bevelled faces.

As shown in Figure 1 the boomerang has a 60 rather steeply bevelled inner surface 7a and a less sloping surface 7b, and the arm 8 has a steeply bevelled outer surface 8a and a less sloping inner surface 8b. The opposite sides of these arms are flat, as shown in Figures 4 65 and 5. These bevelled surfaces cause the boomerang shown in Figures 2 to 5 to deflect to the right when thrown.

The boomerang shown in Figures 6 to 8 70 has an arm 20 which is provided with a steeply bevelled outer surface 20a and with a less sloping inner surface 20b; and with an arm 21 having a steeply bevelled inner edge 21a and a less sloping outer edge 21b. The reverse sides of the boomerang shown in Figure 6 are flat as shown in Figures 7 and 8. The bevels just described cause the boomerang to deflect to the left when thrown. 75

In all the views the boomerang is shown as 80 having an arm one side of which has bevelled faces and the other side of which has a flat face, the implement having also a second arm with bevels reversely arranged except that they are located on the same side of the boomerang. In each instance the two meeting bevels combine to form a projecting or bulging face. 85

It is understood that, although I have illustrated in the drawings the preferred embodiment of the invention, yet I do not intend to limit myself strictly to the precise form illustrated, but may change proportions, angles and size of parts without departing from the spirit of the invention as defined by the claims. 95

I claim:

1. A boomerang having an arm which, as seen in cross section has on one side a relatively steep bevel and also a less sloping bevel, said boomerang having a second arm with 100

similar bevels which are reversely arranged and located on the same side of the boomerang.

2. A boomerang having an arm which, as seen in cross section has on one side a relatively steep bevel and also a less sloping bevel, said arm being bowed and said bevels being on the concave side of said bowed arm.

3. A boomerang provided with two arms, which as seen in cross section are each provided with bevelled surfaces located on the same side of the implement, each of said arms being bowed, said bevelled surfaces being on the concave side of said bowed arms.

4. As a new article of manufacture, a boomerang composed solely of two arms united to form an L shaped structure, each of said arms being bowed, and said arms as seen in cross section being bulged on their concave sides.

5. As a new article of manufacture, a boomerang composed solely of two arms united to form an L shaped structure, each of said arms being bowed, and said arms as seen in cross section being bulged on the same side.

In testimony whereof I hereunto affix my signature.

DON V. TANTLINGER.
